CLAIM

The ornamental design for the “foldable and adjustable multimedia stand for use in gaming to support a steering wheel and pedals,” as shown and described.

DESCRIPTION

FIG. 1 is a rear right perspective view of a foldable and adjustable multimedia stand for use in gaming to support a steering wheel and pedals;

FIG. 2 is a rear left perspective view thereof;

FIG. 3 is a left side perspective view thereof;

FIG. 4 is a rear perspective view thereof;

FIG. 5 is a front perspective view thereof;

FIG. 6 is a bottom plan view; and,

FIG. 7 is a top plan view thereof.
